UNITED STATES PATENT OFFICE.

PHILIP C. MERKER, OF CEDAR RAPIDS, IOWA.

CAR-DOOR.

1,086,603.

Specification of Letters Patent. Patented Feb. 10, 1914.

Application filed October 19, 1912. Serial No. 726,753.

To all whom it may concern:

Be it known that I, PHILIP C. MERKER, a citizen of the United States, residing at Cedar Rapids, in the county of Linn and 5 State of Iowa, have invented a new and useful Car-Door, of which the following is a specification.

The invention relates to improvements in car doors.

10 The object of the present invention is to improve the construction of the car door shown and described in an application filed by me Nov. 22, 1911, Serial No. 661,740, and to equip the same with a ventilating door, 15 adapted to be easily and quickly mounted in the door opening of a freight car in position to coöperate with the lower or main door, when it is desired to change the car door from a storm proof grain tight closure 20 to a ventilating door.

A further object of the invention is to provide means adapted when the lower or main doors are folded against the exterior of the car to protect the same from the drip 25 from the top of the car and at the same time retain the doors in their folded position.

With these and other objects in view, the invention consists in the construction and 30 novel combination of parts hereinafter fully described, illustrated in the accompanying drawings, and pointed out in the claims hereto appended; it being understood that various changes in the form, proportion, size and minor details of construction, within the 35 scope of the claims, may be resorted to without departing from the spirit or sacrificing any of the advantages of the invention.

In the drawings:—Figure 1 is a front elevation of a portion of a car provided with 40 a car door, constructed in accordance with this invention, the ventilating door being in position. Fig. 2 is a similar view, the ventilating door being removed and one of the sectional doors being folded against the side 45 of the car. Fig. 3 is a vertical sectional view on the line 3—3 of Fig. 1. Fig. 4 is a vertical sectional view of the car door, the lower or main door being arranged to form a grain tight closure. Fig. 5 is a horizontal 50 sectional view on the line 5—5 of Fig. 1. Fig. 6 is a similar view on the line 6—6 of Fig. 1. Fig. 7 is an enlarged detail vertical sectional view, taken substantially on the line 7—7 of Fig. 2. Fig. 8 is an enlarged detail sectional view of one of the 55 fixed hinge elements. Fig. 9 is a detail sec-

tional view, illustrating the manner of mounting an eye bolt of the long stay chain. Fig. 10 is a detail view of the bearing plate for the pivoted door engaging bar.

Like numerals of reference designate corresponding parts in all the figures of the drawings.

In the accompanying drawings in which is illustrated the preferred embodiment of 65 the invention, the car door comprises in its construction an upper door 1, a lower or main door, which is composed of four vertical door sections 2, 3, 4 and 5, and a ventilating door 6, the lower or main door and 70 the upper door being adapted to be used together, as illustrated in Fig. 2 of the drawings and in substantially the manner shown and described in the aforesaid application, when it is desired to form a grain tight 75 storm proof closure, and the ventilating door being designed for use in connection with the lower or main door to provide for ventilation, as illustrated in Figs. 1 and 3 of the accompanying drawings. The number 80 of vertical sections of the lower or main door may be increased to provide a door of the desired size, or the vertical sections may be varied in size to secure the same result.

The door sections 2 and 3 are hinged together, and the door sections 4 and 5 are, likewise hinged together forming two sectional doors, which extend from the bottom of the door opening of the side or wall 7 of the car into the upper half of the door 90 opening, the upper door 1 being in the nature of an auxiliary door adapted to be opened in loading grain and designed to remain closed when the merchandise contained within the car is of a size to pass 95 through the door opening when the lower or main door only is open. The sections 2 and 5 of the sectional doors are slidably connected with vertical pintle rods 8 by hinge elements composed of two leaves 9 and 10, hinged together by a vertical pintle 11 and adapted to permit the sectional doors to swing from the door opening of the car to the exterior of the latter to points beyond the said door opening. The leaves 100 9 are riveted or otherwise secured to the outer face of the door sections 2 and 5 at points intermediate of the vertical edges of the same, and the leaves 10, which constitute intermediate leaves, are provided with eyes 110 12 slidably arranged on the vertical pintle rods 8. The vertical pintle rods 8, which

are located at opposite sides of the door opening of the car, are supported at intervals by fixed hinge elements or brackets 13, provided with vertically alined eyes to receive the pintle rods 8 and having horizontal slots 14 through which pass bolts 15, or other suitable fastening devices for securing the hinge elements or brackets 13 in fixed adjustment. The vertical pintle rods 8 are provided with notches 16, located within the vertically alined eyes of the hinge elements 13 and engaged by cotter pins 17, extending through horizontal openings 18 and each having one side cut off and its other side bent at an angle and arranged in a groove 19 formed in the inner or rear face of the hinge elements 13 and extending from the inner end of the opening 18. By this construction, the pintle rod is held 26 against vertical movement in the eyes of the hinge elements 13. No claim is made in the present case to the means for holding the pintle rods against vertical movement. The bolts have their heads arranged at the 25 inner face of the side of the car so as to present smooth surfaces to the contents of the latter. The upper door 1 is connected to the car at the top of the door opening by hinges 20, having horizontal pintles and 30 provided with slots 21 for the reception of suitable fastening devices 22 for adjustably securing the upper door to the car.

The hinge elements or brackets 13 are preferably four in number, and are spaced 35 apart to provide upper, lower and intermediate spaces for the eyes 12 of the leaves 10, and three sets of leaves 9 and 10 are preferably employed, as shown, but the number of fixed hinge elements or brackets and 40 the leaves 9 and 10, which constitute movable hinge elements, may, of course, be varied as desired. The movable hinge elements are slideable vertically on the pintle rods 8 to engage the lower or main door 45 with a groove 23 at the bottom of the door opening of the car and to disengage if therefrom, and also to enable the ventilating door to be placed in position at the lower portion of said door opening. The 50 groove 23 is also adapted to receive one or more wooden blocks or pieces designed to have a skid or runway nailed or otherwise secured to them to prevent the same from dipping. The pintle rods 8 are equipped 55 at the intermediate space with set collars 24, provided with set screws 25 and adapted to be rigidly secured to the pintle rods in engagement with the eyes 12 of the intermediate hinge elements for holding the doors 60 firmly in position against upward movement on the pintle rods when a car is loaded with grain. This will prevent any leakage of the grain at the bottom of the car door. When, however, the car is loaded with a different character of merchandise, the set col-

lars may be arranged at the upper portion of the intermediate space between the fixed hinge elements 13, as illustrated in Fig. 1 of the drawings.

The sections of the lower or main door and the upper door are preferably constructed of heavy sheet metal, such as boiler iron, but any other suitable material, either wood or metal, may be employed in the construction of the door. The hinges 26, which connect the door sections 2 and 3, are preferably arranged at the inner face of the door, and the hinges 27, which connect the door sections 4 and 5, are preferably arranged at the outer face of the door. The hinges 26 and 70 27, which may be constructed in any suitable manner, permit the door sections 2 and 3 to break outwardly and the door sections 4 and 5 to break inwardly. The vertical door sections are bent outwardly at the bottom 75 to provide horizontal bottom flanges 28, and the contiguous vertical edges of the sections 2 and 3 are bent outwardly to form abutting flanges 29 and 30, the flange 29 being L-shaped to cover the joint between the sections 2 and 3. The contiguous vertical edges 80 of the sections 4 and 5 are bent outwardly to form vertical abutting flanges 31, and the section 5 is provided at its inner face with a vertical strip 32, riveted or otherwise secured to the said door section 5 and forming a flange to span and cover the joint between the sections 4 and 5. The adjacent edges of the sections 3 and 4 are bent outwardly to form flanges 33 and 34, the flange 34 being 85 L-shaped in cross section and overlapping the flange 33 to cover the joint.

The car is provided at the bottom of the door opening with a sill plate 35, constructed of sheet metal or other suitable material and angularly bent at the center to form the said groove 23, which has a flat bottom and vertical side walls, the bottom being located slightly below the upper surface of the car floor 36 and forming a drain. The bottom 100 of the groove is provided with openings 37, communicating with passages 38 extending through the bottom of the car and adapted to permit acids or other liquids spilled in the car adjacent to the car door to drain through the openings in the bottom of the groove or gutter. It is the practice on some roads in shipping acid and other liquid liable to injure the other contents of the car to place such liquids close to the door and to nail strips on the bottom or floor of the car to confine any leakage within a limited area. As the bottom of the groove is located below the plane of the surface of the floor, any such leakage will be drained off by the groove or gutter and the openings thereof. The inner and outer portions of the metallic sill or sill plate are inclined and are preferably supported by filler strips 39 of wood or other suitable material, arranged beneath 105 110 115 120 125 130

the sill plate, as clearly illustrated in Fig. 4 of the drawings. The outer inclined portion is adapted to shed water and prevent the same from percolating into the car at the bottom of the door opening.

The groove or gutter besides constituting a drain is also adapted to receive depending studs or projections 40, extending below the lower edges of the door sections and provided with attaching portions secured to the inner faces of the said sections. When the depending studs or projections of the lower or main door are engaged with the groove or gutter of the door sill, the lower portion of the said door is firmly held against either inward or outward movement. The groove or gutter is also adapted to receive depending projections 41 of the ventilating door, which is provided at the top with sockets or openings 42, arranged at intervals in position to receive the depending studs or projections of the lower or main door. The ventilating door, which, as illustrated in the accompanying drawings, consists of vertical bars and horizontal connecting bars, may be of any preferred construction, and can be screened if desired, and it is provided at its ends with projecting flanges 43, arranged in vertical planes and adapted to fit against the outer faces of the vertical flanges 44 at opposite sides of the door opening to prevent the door from being moved inwardly. The vertical flanges 44 are also engaged at their inner faces by horizontal projections or fingers 44^a, fixed to and extending from the outer vertical edges of the door sections 2 and 5. By this construction, the ventilating door is interlocked at the sides and bottom of the car and at the top with the bottom of the lower or main door and is securely retained in position. The vertical flanges 44 consist of sides or wings of angle strips or pieces 45, having their other sides or wings secured to the edges of the car at opposite sides of the door opening. The upper door 1 and the lower or main door are also adapted to fit against the vertical flanges 44 of the angle strips 45, which form tight joints at the sides of the door opening.

The lower edge of the upper door extends below the upper edges of the vertical sections of the lower door, and the said upper door is equipped at its outer face adjacent to its lower edge with a horizontal flanged bar 46, having one of its flanges fitted against the upper door and suitably secured to the same, while the other flange projects horizontally from the said upper door over upper horizontal outwardly extending flanges 47 and 48 of the vertical door sections to provide a tight joint at the top of the lower or main door. The horizontal projecting flange of the bar 46 is provided at intervals with slots 49, adapted to be engaged by a pointed bar or other tool to en-

able the vertical sections of the lower door to be forced inwardly into position, and permitting the bills of hooks 50 to project through the said horizontal flange of the bar 46 for engaging the upper ends of the vertical sections of the lower or main door for securing the same in tight engagement with the lower edge of the upper door and for fastening the latter in its closed position. The hooks 50, which are pivoted, are designed to be constructed similar to those described in the aforesaid application.

The lower or main door is equipped with a pivoted door engaging bar 51, mounted on the vertical door section 3 and being of a length to extend entirely across the door sections 3 and 4 and overlap the inner portions of the sections 2 and 5. The ends of the door engaging bars are equipped with reversely arranged hooks 52, adapted to engage horizontally disposed handles 53 mounted on the door sections 2 and 5 and forming loops and performing the double function of a keeper and a handle. The door section 4 is equipped with an inverted approximately U-shaped keeper 54, arranged in the path of and adapted to be engaged by the pivoted locking bar 51. The pivoted bar is secured in its engaging position by mechanism adapted to receive a seal 55, which is provided at its upper end with a pin 56 adapted to engage an opening in the horizontally projecting flange of the upper door. The seal receiving means for locking the pivoted bar is constructed similar to that shown and described in the aforesaid application, and as no claim is made in the present application to the locking means for securing the upper door 1 and the lower or main door in their closed positions, further description and illustration thereof are deemed unnecessary.

When the sectional doors of the lower or main door are folded against the outer face of the car, they are arranged beneath hinged shields 57 having their upper edges disposed horizontally at opposite sides of the door opening and constructed of sheet metal, or other suitable material, bent longitudinally at 58 adjacent to their lower edges to form angularly related upper and lower portions and having their lower edges bent upwardly to provide bottom flanges 59 and to form exterior grooves or gutters 60, adapted to carry the drip beyond the vertical edges of the folded sectional doors. When the sectional doors are folded beneath the shields, the upper portions of the latter extend downwardly and outwardly at an inclination from the outer face of the car, and the lower portions, which have the grooves or gutters, are arranged in a substantially vertical plane. The shields 57 are provided adjacent to their upper edges with perforations 61, 130

which are linked into eyes 62, whereby they are hinged to the side of the car and adapted to swing upwardly and downwardly to enable the sectional doors to be swung beneath them and removed from such position. The hinged shields are also equipped at their outer portions with upwardly projecting claws 63, consisting of plates or pieces secured to the flanges 59 and extending upwardly therefrom and provided in their projecting portions with slots or bifurcations adapted to receive links of short chains 64, secured to the upper portions of the adjacent vertical door sections. These short chains are adapted to be readily engaged with and disengaged from the claws of the shields, and they are secured to the sectional doors in their folded position beneath the shields and prevent the doors from swinging outward and coming in contact with cars and other objects.

The upper door 1 swings inwardly and upwardly in opening, and it is held in the open position, illustrated in dotted lines in Fig. 3 of the drawings, by a gravity catch 65, constructed and arranged as shown and described in the aforesaid application, and as no claim is made to the same herein further description thereof is unnecessary.

30 When the car is designed to be loaded with grain, the lower or main door may be braced by a stay chain 66, provided at its upper end with a ring 67, which is permanently linked into an eye bolt 69 of the door sections 3 and having a hook 68 at its lower end to engage a ring 70, or other anchoring means located at the floor of the car in spaced relation with the door. The ring 70 is linked into an eye bolt 71, but the latter may be directly engaged by the hook 68 if desired. The vertical door section 4 is also equipped with a short chain 72 provided at its free portion with a terminal link or ring 73 and an intermediate link or ring 74, located a short distance from the terminal link. The inclined chain 66 is adapted to pass through the intermediate link 74, and the short stay chain 72 extends upwardly and inwardly from the vertical door section 4 to the stay chain 66 for bracing the sectional door to which it is connected. The terminal link 73 of the stay chain 72 is adapted to be connected with the inclined chain 66, when it is desired to provide a small amount of slack in the chain 72 to allow for a slight separation of the sectional doors for ventilating purposes. These chains are also adapted to be employed with any heavy load where there is small danger 60 of the contents of the car shifting and contacting with the stay chains, and should it be desired to use the stay chains when the ventilating door is employed, any suitable means such as a piece of wire or an addi-

tional chain may be utilized to lengthen the 65 chain 66 and connect the same with anchoring means to the floor of the car.

The lower or main door is equipped on its exterior with a short chain 75 secured at one end to the door section 3 and adapted to be secured to a projecting ear or lug 76, extending horizontally from the door section 4 and provided with a perforation 77 through which is passed a pin 78 or other suitable fastening means for confining a 75 link of the chain 75 on the lug or ear 76. The pin 78 may be sealed and the chain 75 can be utilized in the event of breakage of the seal receiving means for locking the door engaging bar.

80 The eye bolt 69 is mounted in a bearing plate 79, secured to the outer face of the door section 3 and provided with a central opening 80 to receive the shank portion of the eye bolt and having an elongated recess 81 at its inner face to receive a portion of the eye of the bolt 69, whereby the latter is held against rotary movement. The door section 3 is provided with a slot 82, which registers with the recess 81 of the bearing 90 plate 79, and the latter has an annular bearing flange 83, surrounding the opening 80 and extending from the outer face of the plate 79 and forming a journal or pivot for the door engaging bar 51. The threaded portion of the eye bolt 69 extends beyond the flange 83 and receives a nut 84, which is screwed tightly against the outer edge of the flange 83. The flange 83 is of a length slightly in excess of the thickness of that 100 portion of the door engaging bar through which it passes, so that the screwing of the nut against the flange does not affect the free pivotal movement of the door engaging bar.

105 What is claimed is:

1. The combination with a car having a door opening, of an upper door hinged to the car at the top of the opening and arranged to swing upwardly and downwardly, 110 lower sectional doors hinged to the car at opposite sides of the door opening and co-operating with the upper door to close the said opening, said lower sectional doors being slidably upwardly and downwardly and 115 adapted to be arranged in an elevated position in the door opening, and a ventilating door arranged in the lower portion of the door opening and supporting the sectional doors and detachably interlocked with the 120 same and with the car.

2. The combination with a car having a door opening, of sectional doors hinged to the car at opposite sides of the door opening and slidably upwardly and downwardly 125 and adapted to be arranged in an elevated position, and a ventilating door arranged in the lower portion of the door opening

and supporting the sectional doors and detachably connected with the same and with the car.

3. The combination with a car having a door opening provided at the bottom with a groove or gutter, of sectional doors hinged to the door opening at opposite sides thereof and slideable upwardly and downwardly and provided at their lower ends with studs or projections to engage with the groove or gutter when the sectional doors are in their lowermost position, and a ventilating door adapted to support the sectional doors in an elevated position and provided at the top with openings or sockets to receive the said studs or projections and having depending projections at the bottom to engage with the groove or gutter.

4. The combination with a car having a door opening and provided at opposite sides thereof with vertical flanges, of sectional doors hinged to the car at opposite sides of the door opening and slideable upwardly and downwardly and fitting against the vertical flanges, and a ventilating door arranged in the lower portion of the door opening and supporting the sectional doors in an elevated position and provided at its ends with flanges fitting against the outer faces of the said vertical flanges and interlocking the ventilating door with the car.

5. The combination with a car having a door opening and provided at opposite sides thereof with vertical flanges and having a groove or gutter at the bottom of the door opening, of sectional doors hinged to the car at opposite sides of the door opening and slideable upwardly and downwardly and provided at the bottom with depending studs or projections to engage the groove or gutter, and a ventilating door arranged within the lower portion of the door opening and provided at the top with openings or sockets to receive the said lugs or projections and having depending projections at the bottom to engage with the groove or gutter and provided at its ends with projecting flanges to engage with the vertical flanges of the car.

50 6. The combination with a car having a door opening and provided at opposite sides thereof with pintle rods and having a groove or gutter at the bottom of the said opening, of sectional doors having hinge elements slideable on the pintle rods, and set collars adjustably arranged on the pintle rods and adapted to engage with the hinge elements of the said doors for retaining the latter in interlocked relation with the groove or gutter.

6. The combination with a car having a door opening and provided at the bottom thereof with a groove or gutter, pintle rods mounted on the car exteriorly thereof at opposite

sides of the door opening, doors provided with movable hinge elements slidably mounted on the pintle rods and extending into the door opening to permit the doors to be engaged with and disengaged from the said groove or gutter, and exterior set collars mounted on the pintle rods and having clamping means for engaging the same, said set collars being adapted to hold the movable hinge elements against upward movement on the pintle rods to retain the doors in engagement with the groove or gutter of the bottom of the car.

8. The combination with a car having a door opening, of a hinged door mounted at the said door opening and arranged to swing substantially flat against the exterior of the side of the car beyond the door opening, and a shield hinged at its upper edge to the exterior of the car and also located beyond the door opening and extending below the plane of the upper edge of the door and lying against the latter, said shield being arranged to swing upwardly and downwardly to permit the door to swing horizontally beneath it and adapted to protect the door and retain the same in its open position against the side of the car.

9. The combination of a car having a door opening, sectional doors hinged to the car at opposite sides of the door opening and foldable against the exterior of the car, and shields hinged at their upper edges to the car and also located beyond the door opening and extending below the plane of the upper edge of the doors and adapted to swing upwardly and downwardly to permit the doors to swing horizontally beneath them, said shields being adapted to protect the doors and retain the same in their open position.

10. The combination of a car having a door opening, sectional doors hinged to the car at opposite sides of the door opening and foldable against the exterior of the car, shields hinged at their upper edges to the car and also located beyond the door opening and extending below the plane of the upper edge of the doors and adapted to swing upwardly and downwardly to permit the doors to swing horizontally beneath them, and coacting means on the shields and doors for securing the former to the latter and for holding the doors in their folded position.

11. The combination of a car having a door opening, sectional doors hinged to the car at opposite sides of the door opening and foldable against the exterior of the car, shields hinged at their upper edges to the car and also located beyond the door opening and extending below the plane of the upper edge of the doors and adapted to swing upwardly and downwardly to permit

the doors to swing horizontally beneath them, claws projecting upwardly from the exterior of the shields, and chains carried by the sectional doors and engaging the claws for retaining the doors in their folded position beneath the shields.

12. The combination of a car having a door opening, sectional doors hinged to the car at opposite sides of the door opening 10 and foldable against the exterior of the car, shields hinged at their upper edges to the car and also located beyond the door opening and extending below the plane of the upper edge of the doors and adapted to 15 swing upwardly and downwardly to permit the doors to swing horizontally beneath them, said shields having angularly related upper and lower portions and provided at their lower portions with exterior grooves 20 or gutters.

13. A car having a door opening and provided at the bottom with a sill plate constructed of sheet metal and provided with a central longitudinal groove or gutter having 25 vertical side walls and a connecting horizontal bottom, the latter being seated upon the floor of the car, said sill plate being also provided with inclined inner and outer portions formed integral with the said vertical 30 walls and extending downwardly from the upper edges thereof to the floor, and transversely tapered filler strips arranged at opposite sides of the groove or gutter between the vertical walls thereof and the said inclined inner and outer portions and supporting the latter.

14. The combination with a car having a door opening, of sectional doors hinged to the car at opposite sides of the door opening, a relatively long inclined stay chain ex- 40

tending from one of the sectional doors and connected with the bottom of the car, and a relatively short stay chain connected with the other sectional door and having spaced links or rings through which the relatively 45 long chain is adapted to pass.

15. The combination of a car having a door opening and provided at opposite sides thereof with vertical flanges, vertical pintle rods mounted on the exterior of the car beyond the said flanges, doors fitting against the outer faces of the flanges and having hinge elements arranged on the pintle rods, and rigid fingers projecting from the doors and arranged to engage the said vertical 55 flanges at the inner faces thereof when the doors are closed.

16. The combination with a car, of door sections hinged to the car, a bearing plate secured to one of the door sections and provided with a bolt opening and having an elongated recess at the inner end thereof and provided at the outer end of the same with a projecting annular flange, and an eye bolt passing through the said plate and having its eye fitted in the recess thereof and its threaded portion projecting beyond the bearing flange, a door engaging bar mounted on the bearing flange, a nut arranged on the threaded portion of the eye bolt and bearing 70 against the said flange to retain the door engaging bar thereon, and a stay chain connected with the eye of the bolt.

In testimony, that I claim the foregoing as my own, I have hereto affixed my signature in the presence of two witnesses.

PHILIP C. MERKER.
